United States Patent Office

Des. 211,752

Patented July 23, 1968

211,752

PORTABLE MANUALLY OPERATED SCRAPER HANDLE

Harold A. Rippl, 223 Westbridge Drive,
Berea, Ohio 44017

Filed Jan. 26, 1967, Ser. No. 5,573

Term of patent 14 years

(Cl. D49—26)

Fig. 1.

Fig. 2.

Fig. 3.

FIG. 1 is a top perspective view of a portable manually operated scraper handle showing my new design.

FIG. 2 is a side elevational view; and

FIG. 3 is a bottom perspective view of the scraper handle.

The dominant features of my design reside in those portions thereof which are shown in solid lines.

I claim:

The ornamental design for a portable manually operated scraper handle, as shown and described.
